UNITED STATES PATENT OFFICE.

HAROLD CROSS, OF LOS ANGELES, CALIFORNIA.

AUTOMATIC DISCHARGE-VALVE FOR LAVATORIES AND THE LIKE.

1,287,247.

Specification of Letters Patent. Patented Dec. 10, 1918.

Application filed February 21, 1918. Serial No. 218,465.

To all whom it may concern:

Be it known that I, HAROLD CROSS, a citizen of the United States, residing at Los Angeles, in the county of Los Angeles and 5 State of California, have invented new and useful Improvements in Automatic Discharge-Valves for Lavatories and the like, of which the following is a specification.

My object is to make an automatic discharge valve for lavatories and the like, the 10 valve having manual means for discharging when desired, and my invention consists in the novel features herein shown, described and claimed.

15 Figure 1 is a fragmentary sectional perspective showing an automatic discharge valve embodying the principles of my invention in position for use.

Fig. 2 is a horizontal sectional detail on 20 the line 2—2 of Fig. 1.

Fig. 3 is a vertical cross-section on the lines 3—3 of Figs. 1 and 2.

Fig. 4 is a fragmentary vertical section on the line 4—4 of Fig. 1.

25 The upper end of the discharge pipe 1 has an annular flange 2 projecting inwardly, the flange 2 being some distance below the extreme upper end face 3. A supporting flange 4 extends outwardly to increase the 30 size of the upper face 3. A gasket 5 is inserted into the discharge opening 6 of the bowl 7, said gasket being L-shaped in cross-section and the lower face of the gasket resting upon the upper face 3 of the discharge pipe. A sleeve 8 is inserted downwardly through the opening 6 of the bowl 35 and has a flange 9 engaging the inner face of the bowl around the opening 6, and the sleeve fits closely in the opening 6 and is off-set inwardly to pass the gasket 5 and then extends downwardly and fits closely in the discharge pipe 1. The valve casing 40 is cylindrical and is inserted downwardly in the sleeve 8 and rests upon the flange 2. A strainer 11 is inserted downwardly into the sleeve 8 and rests upon the shoulder 12, so that the upper face of the strainer is flush with the upper face of the flange 9.

45 The details of the valve 13 in the valve casing 10 are as follows:

The circular flat valve 14 is adapted to fit in the casing 10 and is pivotally supported by set-screws 15 and 16 inserted through the casing 10 loosely into openings 50 in the periphery of the valve, said pivots being upon the line 17 to one side of the

center point 18 so that the portion 19 of the valve will have a greater area than the portion 20. A stop flange 21 extends inwardly from the casing 10 under the portion 60 20 and a similar stop flange 22 extends from the casing 10 over the portion 19, so that when the valve is horizontal and closed, as in Fig. 3, the portion 19 swings upwardly 65 against the flange 22 and the portion 20 swings downwardly against the flange 21. The valve is counterbalanced by a weight 23 extending downwardly from the portion 20, the gravity of the weight 23 being sufficient, when added to the weight of the portion 20, to overbalance the portion 19 and close the valve and to hold the valve closed with a small quantity of liquid resting upon the valve and filling the upper part of the casing 10 and flooding the strainer 11. A 70 pocket 24 is formed in the weight 23 and opening toward the periphery of the portion 20 so that when the valve is horizontal the pocket 24 is empty and when the valve swings to its vertical open position, as shown 75 in dotted lines in Fig. 3, the pocket is in position to catch liquid coming through the strainer and the weight of this liquid is sufficient to counterbalance and close the valve. As the bowl 7 fills with water above 80 the strainer 11 the weight of the water upon the portion 19 will overbalance the weight of the portion 20 and the weight 23 and automatically open the valve and discharge the water. Then when the pocket 24 fills 85 with water the valve will be automatically closed, in fact the pocket will be filled with water and will retain this water as the water discharges from the bowl and when the flow ceases the valve will immediately close. 90

95 A rock-shaft 25 is mounted in a bearing 26 extending from the discharge pipe 1, a crank 27 extends from the inner end of the shaft, and a crank pin 28 carrying an arm 28' extends from the crank under the portion 100 20 of the valve. An arm 29 extends from the outer end of the shaft 25 upwardly and outwardly at an angle of about forty-five degrees. A push-button 30 is formed upon the upper end of a push-rod 31 mounted at 105 one side of the bowl 7 and a bearing 32 at the lower end of the push-rod 31 has an opening 33 through which the arm 29 extends. A spring 34 holds the rod 31 in its normal elevated position. When, for any 110 reason, it is desired to discharge the valve, the push-button 30 is pressed downwardly,

and the push-rod 31 slides downwardly to operate the arm 29 and rotate the shaft 25 to operate the pin 28 carrying the arm 28' to swing upwardly against the bottom of the portion 20 and discharge the valve. By the operation of the push-button 30 the valve may be discharged at any time but it cannot be held closed.

Thus I have produced a valve which will hold a certain amount of liquid for the purpose of flooding the parts and sealing the joints and which will automatically discharge when the amount of liquid is increased beyond a certain point and which may be manually discharged at any time.

Various changes may be made in the details of construction without departing from the spirit of my invention as claimed.

I claim:

- 20 1. The combination with an automatic valve, of a shaft, a crank extending from the shaft, a pin extending from the crank and engaging under the short side of the valve, and a push-rod connected to the shaft for rotating the shaft and operating the crank pin to discharge the valve.
- 25 2. In an automatic valve, a casing, a circular flat valve pivotally mounted in the

casing with more supporting area on one side of the pivot than on the other, flanges 36 extending from the casing to be engaged by the valve in its closed position to form joints, and a pocketed counterbalancing weight extending from the lower face of the short portion of the valve and adapted 35 to counterbalance the valve to support a certain amount of liquid and to be overbalanced by an excess of liquid and the pocket being adapted to fill with liquid when the valve is overbalanced to restore 40 the valve to its normal closed position.

3. The combination with an automatic valve, of a shaft, a crank extending from the shaft, a pin extending from the crank and engaging under the short side of the 45 valve, an arm extending from the outer end of the shaft; said arm being at an angle of about forty-five degrees upwardly and outwardly from the shaft when the valve is closed; and a push rod mounted at one side of the shaft and having a bearing at its lower end through which the arm extends loosely.

In testimony whereof I have signed my name to this specification.

HAROLD CROSS.
